UNITED STATES PATENT OFFICE.

GEORGE E. ADAMS, OF NEW BRITAIN, CONNECTICUT.

DESIGN FOR A GARMENT-SUPPORTER LOOP.

SPECIFICATION forming part of Design No. 31,912, dated November 28, 1899.

Application filed October 27, 1899. Serial No. 734,993. Term of patent 14 years.

To all whom it may concern:

Be it known that I, GEORGE E. ADAMS, a citizen of the United States, residing at New Britain, in the county of Hartford and State of Connecticut, have invented and produced a new and original Design for Garment-Supporter Loops, of which the following is a specification, reference being had to the accompanying drawings, forming part thereof.

10 In the drawings, Figure 1 is a front elevation of a loop embodying the present design. Fig. 2 is an end elevation.

15 The leading or characteristic features of the present design are the relatively long and narrow loop at the top, with the narrow transverse loop extending down centrally from one of its sides, together with the beaded edges of the downwardly-extending loop.

The letter A indicates the long narrow loop a, the bottom bar having the downwardly-offset portion a'.

20 B indicates the bottom loop extending down from the offset portion a'. Oppositely-arranged circular concavities C are formed in the loop B near the bottom, and rounded beads 25 D extend down around the edges of the loop, as shown.

What I claim is—

25 The design for a garment-supporter loop, as herein shown and described.

GEORGE E. ADAMS.
